BOOKRACK

Harold B. Pickering and Edythe Marie Pickering,
Manhasset, N. Y.

Application April 26, 1933, Serial No. 668,010
Renewed January 19, 1935

1. Claim. (Cl. 45—58)

This invention relates to new and useful improvements in book racks.

It is the object of the present invention to provide a simple, inexpensive and yet ornamental rack for books and particularly for books bound by means of a spiral spring screwed into perforations near the edges of book leaves such as is described in Patent No. 1,516,932, of November 25, 1924 to L. Staab.

10 With this object in view, we provide two pins in the rack so spaced from one another and the rack that the ends of the spring at the edge of the book may be readily held thereby.

15 A preferred embodiment of the invention is illustrated in the drawing in which—

Fig. 1 is a front elevation of a rack holding a book, and

Fig. 2 shows an opened book which has been removed from the rack.

20 The book leaves 1 are bound together by means of a spiral spring 2 screwed into perforations 3 near the edges of the leaves, the spacing of the spring spirals being equal to that of the perforations. The spring 2 is of substantially the same length as the book.

25 The rack proper consists of a flat surface 4 which may be surmounted by a decoration 5

characteristic of the nature of the books. Pins 6 and 7 are fastened to the flat surface 4. The longitudinal axes of the pins are in alignment with one another and parallel to the surface 4. The spacing between the pins and the surface 4 is such that a book may be inserted between the two pins and by slightly flexing the spring 2 and then allowing it to straighten, the pins 5 and 6 will project within the convolutions of the spring at the ends thereof. The diameter of the pins is smaller than that of the spring spirals. The book can be readily removed by grasping the spring 2 near its center.

What is claimed is:

15 In a rack for books having a binding consisting of a spiral spring screwed into perforations of the book leaves near the edges thereof, a flat surface and two pins fastened to said surface in alignment with one another and with their longitudinal axes parallel to but in a different plane than said surface, the distance between the opposing ends of the pins being less than the length of said spring and the diameter of the pins being less than the diameter of the spring convolutions.
